(57) CLAIM

An ornamental design for a sleeve, as shown and described.

DESCRIPTION

FIG. 1 is a top perspective view of a sleeve showing our new design;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof; and,

FIG. 8 is an exploded top perspective view thereof.

The portions of the article in broken lines are shown for illustrative purposes only and form no part of the claimed design.
